UNITED STATES PATENT OFFICE.

WALTER SHAW, OF DEDHAM, MASSACHUSETTS, ASSIGNOR TO UNITED SHOE MACHINERY CORPORATION, OF PATERSON, NEW JERSEY, A CORPORATION OF NEW JERSEY.

PRESSER-FOOT-OPENING MECHANISM.

1,315,243.

Specification of Letters Patent.

Patented Sept. 9, 1919.

Application filed December 17, 1917. Serial No. 207,536.

To all whom it may concern:

Be it known that I, WALTER SHAW, a citizen of the United States, residing at Dedham, in the county of Norfolk and State of Massachusetts, have invented certain Improvements in Presser-Foot-Opening Mechanisms, of which the following description, in connection with the accompanying drawings, is a specification, like reference characters on the drawings indicating like parts in the several figures.

This invention relates to fastener inserting machines and, more particularly, to those elements which guide and clamp the work while it is being fed and maintain it in proper position when it is at rest.

The invention is of particular utility in connection with duplex eyeleting machines which are arranged for corset work and, although it will become obvious that its field of use is not limited to this particular machine or class of machines, the problem will be considered as it arose in connection with such a machine.

Duplex eyeleting machines are commonly equipped with clamping members on presser feet of the type shown in Letters Patent of the United States No. 1,030,833, granted June 25, 1912, upon the application of F. A. Rumney. The work is inserted between these clamping members by sliding it edgewise between them, whether they are used with or without an intermediate plate such as that disclosed in the co-pending application of F. A. Rumney, Serial No. 857,760, filed Aug. 20, 1914. With certain types of work, however, notably corsets in which heavy bones have been inserted or corsets having no bones, considerable effort is required to push the work into place.

An object of the invention is to provide novel and convenient means for separating the work guiding and clamping members to facilitate the insertion of work.

Various arrangements of presser feet have been suggested in which the two clamping members were articulated or otherwise interconnected so as to be incapable of moving independently of each other. This made the opening of the clamping members a simple matter as retraction of one member would cause corresponding movement of the other. Such arrangements, however, involve the difficulty that an increase in the thickness

of one of the two superposed layers of work will cause the tension to be lessened upon the other layer with the result that the feeding movements imparted to the two pieces of work may not be equal and hence that the eyelets which are set may not be located exactly opposite to each other.

A feature of the invention relates to an arrangement of the presser feet opening mechanism which will avoid such difficulties while allowing independent action of the presser feet as heretofore, thus retaining the well known advantages of such action; the construction and arrangement, as shown, being such that equal separating movement will be imparted to the presser feet regardless of their relative positions prior to the separating movement.

In the illustrated arrangement the presser feet are interconnected by a manually operable flexible member which is constructed and arranged to exert equal tension on each of the presser feet whatever their position when the tension is applied, and which are also constructed and arranged to allow independent movement of the presser feet when the flexible member is under tension and to allow conjoint movement of the presser feet regardless of whether or not the flexible member is tensioned.

Other features of the invention relate to the connections between the tensioning means, here illustrated as a foot treadle, and the presser feet separating means, which connections are arranged to prevent the unintentional transmission of tension from the treadle to the separating means and which are also provided with means for preventing the separating means from becoming unduly slackened under the action of a spring inserted in the connections.

In the following specification and the accompanying drawings there is described and illustrated a specific embodiment of the invention as applied to a particular machine. The invention is, however, not limited to the specific form shown and described, nor is its use limited to this particular machine, the scope of the invention being defined in the appended claims.

In the drawings:—

Figure 1 is an angular view showing the invention applied to a duplex corset machine of the type illustrated in Letters Patent of

the United States No. 1,231,201, granted June 26, 1917, upon the application of F. A. Rumney.

Fig. 2 is a fragmentary section through the work support adjacent to the presser feet.

The machine is ordinarily supported upon a bench or table 10 and comprises a main frame 12 to which is bolted an auxiliary frame 14. In this frame the hammer levers 16, only one of which is shown, are pivoted. The operating tools are supported in a bifurcated frame 18 which is pivoted in one arm of the bell crank 20 for back and forth and lateral movement. These movements are guided by the stud 22 in coöperation with the track 24. Supported in the frame 18 and interposed between the tools is a combined die plate and punch plate 26 which coöperates with the sets 28 and punches 30. Suitable hammers 32 and 34 are provided for the operation of the sets and punches respectively, and it will be noted that the hammers 34 are provided with hooks 36 and 38 engaging offsets upon the punches to insure their positive retraction. Retraction of both the sets and punches is also assisted by means of the usual spring actuated levers. A work guiding trough 40 of the type shown in the Rumney Patent No. 1,231,201, is mounted upon the frame of the machine.

Adjacent to the end of the work guide 40 and between it and the intermediate plate 26, are co-acting presser feet 42 and 44 which are resiliently mounted upon a block 46 capable of back and forth adjusting movement when actuated by a lever 48. The operation of separating these presser feet is accomplished by tensioning a cord, 40 preferably in the form of a wire cable 50 which is attached at its ends to the presser feet and which passes over a guiding pulley 52 supported by means of a clamp 54 upon the frame 14. This cable 45 also passes through guides 56 at the rear of the work support 40 and around the tensioning pulley 58, which is connected by means of rods 60 and 62 and a lever 64 to the crank 66 upon the treadle rod 68. The 50 crank 66 is attached to an offset 70 upon the treadle rod and a treadle 72 of usual or suitable construction is provided. This treadle is commonly and preferably also utilized for tripping the clutch which starts 55 the machine in operation and is arranged to effect this tripping when its forward or toe end is depressed. A spring 74 is interposed between the pulley 58 and the table 10 while a stop 76 upon the rod 60 is arranged to limit the upward movement of 60 said rod under tension of the spring 74.

In Fig. 2, the work 80 is shown as clamped directly between the presser feet 42 and 44 without the interposition of the 65 intermediate plate. The separation of these

presser feet to allow the insertion of the work is readily effected by depressing the heel end of the treadle 72. By reason of the provision of the pulleys 52 and 58, the separating tension which is exerted upon 70 the clamping means or presser feet will be equalized notwithstanding various initial positions thereof, and the arrangement will allow free conjoint movement of the work and presser feet regardless of the action 75 of the manually operated cable tensioning means. A further advantage of applicant's novel arrangement lies in the fact that any movement communicated to one of the presser feet, as, for example, by a variation 80 in the thickness of the work, will not be communicated through the cable 50 to the other presser foot and, therefore, there will be no tendency of such inequalities to cause relief in the work clamping tension exerted by the other presser foot upon the work. Because of the large number of eyelets to be set, this feature becomes of particular importance in corset work since it is very essential that there be no variation 85 in the feed movements of the two halves of the work, if perfect alinement of the eyelets in the halves is to be secured. The spring 74 tends to prevent the tensioning of the cable 50 by an unintentional pressure of 90 the operator's foot upon the heel end of the treadle 72. Such a pressure might otherwise cause an undesirable opening of the presser feet and, therefore, might destroy uniformity of the feeding effect which 95 normally is practised by the machine. The stop 76 upon the rod 60 will, it will be seen, prevent the cable from becoming unduly slack when the toe end of the treadle 72 is depressed in tripping the clutch. 100

Having thus described the invention, what is claimed as new and desired to be secured by Letters Patent of the United States is:—

1. In a fastener-inserting machine, coöperative work-clamping members movable toward and from each other independently of each other, and means for separating said members constructed and arranged to equalize the separating stresses applied to 110 said members.

2. In a fastener-inserting machine, coöperative work-clamping members movable toward and from each other, and manually operative means connected to said clamping members separately to retract each from the other, said means being arranged to equalize the separating stresses applied to 115 said members.

3. In a fastener-inserting machine, coöperative work-clamping members movable toward and from each other, flexible means connected to each of said clamping members separately, and means arranged to operate said flexible means to retract said 120

clamping members from each other, said flexible means and said operating means being arranged to equalize the retracting stresses applied to the clamping members.

- 5 4. In a fastener inserting machine, duplex fastener inserting mechanism constructed and arranged to operate upon superposed layers of work, work guiding mechanism, co-acting superposed presser feet, a cord connecting said presser feet, and a guiding pulley and an actuating pulley for said cord constructed and arranged to cause a separating movement of said presser feet upon the tensioning of said cord 10 through movement of said actuating pulley.
- 15 5. In a fastener inserting machine, coöperative presser feet constructed and arranged to clamp superposed layers of work, means interconnecting said presser feet constructed and arranged to permit movement 20

of one of the presser feet independently of the other, manually operative means arranged to actuate the first said means to separate the presser feet, and means tending to prevent unintentional actuation of 25 said manually operative means.

6. In a fastener inserting machine, presser feet constructed and arranged to clamp superposed layers of work, means interconnecting said presser feet constructed 30 and arranged to separate the presser feet, tensioning means for the separating means, means tending to relieve the tension upon said separating means, and means for preventing said separating means from becoming unduly slackened. 35

In testimony whereof I have signed my name to this specification.

WALTER SHAW.
